UNITED STATES PATENT OFFICE.

THOMAS HARDIE, OF PHILADELPHIA, PENNSYLVANIA, ASSIGNOR TO PHILADELPHIA STEEL & IRON COMPANY, OF PHILADELPHIA, PENNSYLVANIA, A CORPORATION OF NEW JERSEY.

MUFFLE-FURNACE.

SPECIFICATION forming part of Letters Patent No. 739,174, dated September 15, 1903.

Application filed January 10, 1903. Serial No. 138,487. (No model.)

To all whom it may concern:

Be it known that I, THOMAS HARDIE, a citizen of the United States, residing at the city of Philadelphia, in the county of Philadelphia and State of Pennsylvania, have invented certain new and useful Improvements in Muffle-Furnaces, of which the following is a specification.

The principal object of the present invention is to provide for the production of a uniformly high heat in every portion of the furnace.

Another object of the invention is to provide a furnace well adapted for annealing and for processes where conversions are brought about under an even heat.

To these and other ends hereinafter set forth the invention comprises the improvements to be presently described and claimed.

The nature, characteristic features, and scope of my invention will be more fully understood from the following description, taken in connection with the accompanying drawings, forming part hereof, and in which—

Figure 1 is a top or plan view of a furnace embodying features of the invention. Fig. 2 is a vertical sectional view taken on the line 2 2 of Fig. 1. Fig. 3 is a horizontal sectional view taken on the line 3 3 of Fig. 2, and Fig. 4 is a sectional view taken on the line 4 4 of Fig. 3.

In the drawings the furnace is shown as of generally rectangular form in plan and as constructed of suitable masonry, the top being arched.

1 and 2 are fireplaces arranged at the sides of the externally-heated chamber 3.

4 is a subdivided floor-flue, having a chimney-outlet 5. The subdivisions are produced by means of baffle-walls 6, as shown. There are crown-flues, of which some, 7, extend from the fireplace 1 across the top of the chamber 3 and to the right-hand side of the floor-flue

4, and of which others, 8, extend from the other fireplace 2 across the top of the chamber and to the left-hand side of the floor-flue 4. As shown, the flues 7 and 8 alternate with each other.

In use the articles to be heated are placed in the chamber 3 and proper fires are made in the fireplaces 1 and 2. The hot products from these fireplaces traverse the flues 7 and 8 in opposite directions and crosswise of the furnace and then reach the floor-flue 4 and travel back and forth lengthwise of the furnace past the baffle-walls and reach the off-take 5. In this way the chamber 3 is externally heated and the heat is distributed throughout it with marked uniformity.

It will be obvious to those skilled in the art to which my invention appertains that modifications may be made in detail without departing from the spirit thereof. Hence I do not limit myself to the precise construction and arrangement of parts hereinabove set forth, and illustrated in the accompanying drawings; but,

Having thus described the nature and objects of my invention, what I claim as new, and desire to secure by Letters Patent, is—

A muffle-furnace comprising fireplaces arranged at the sides of an externally-heated chamber, a longitudinally-subdivided floor-flue having a chimney-outlet, and crown-flues of which some extend from one fireplace across the top of the chamber and to one side of the floor-flue and of which others extend from the other fireplace across the top of the chamber to the other side of the floor-flue, substantially as described.

In testimony whereof I have hereunto signed my name.

THOS. HARDIE.

In presence of—

ALLAN J. CASSIDY,
FRED. W. CASSIDY.
